UNITED STATES PATENT OFFICE.

SAMPSON SCHUYLER, OF LONG BRANCH, NEW JERSEY.

GAME DEVICE.

1,252,957.

Specification of Letters Patent.

Patented Jan. 8, 1918.

Application filed March 28, 1917. Serial No. 157,874.

To all whom it may concern:

Be it known that I, SAMPSON SCHUYLER, a citizen of the United States, and residing at Long Branch, in the county of Monmouth 5 and State of New Jersey, have invented certain new and useful Improvements in Game Devices, of which the following is a specification, such as will enable those skilled in the art to which it appertains to make and

10 use the same.

This invention relates to game devices and the object thereof is to provide a device of this class which is designed to amuse both young and old, but the successful playing 15 of which will involve a greater or less degree of skill and experience; a further object being to provide a game device which involves a number of movable parts, but which is simple in construction, and strong 20 and durable and will not easily get out of order and thus necessitate repairs.

The invention is fully disclosed in the following specification, of which the accompanying drawing forms a part, in which the 25 separate parts of my improvement are designated by suitable reference characters in each of the views, and in which:—

Figure 1 is a plan view of my improved game device with part of the construction 30 broken away and indicating the method of playing the same;

Fig. 2 a longitudinal section on the line 2—2 of Fig. 1;

Fig. 3 a transverse section on the line 3—3 35 of Fig. 1;

Fig. 4 an enlarged view of one of a number of perforated balls which I employ; and,

Fig. 5 a view of the ball shown in Fig. 4 40 but at right angles thereto.

In the accompanying drawing, I have 45 shown at *a* a support, comprising a top member *a*², legs *a*³ and brace members *a*⁴ connected with said legs, and the top member *a*², in the construction shown, is inclined upwardly and backwardly; and in the practice 50 of my invention, I provide a box or casing *b* which is adapted to be mounted on the support and the bottom *b*² of which is inclined at an angle corresponding to that of the top *a*² of the support.

The construction of the support, however, or the inclination of the top thereof, is not essential as the box or casing might be placed on any table or support and one end of said

box or casing raised in any way so as to 55 permit of the operation of playing the game as hereinafter described.

The box or casing *b* comprises side walls *b*³, a front wall *b*⁴, a back wall *b*⁵ and a supplemental bottom or table *c* which is also 60 inclined upwardly and backwardly, said bottom or table being preferably provided with a felt or similar covering *c*² as shown in Fig. 2.

The front end of the supplemental bottom *c* is connected with the bottom *b*² by a vertical member *c*³ which is set inwardly of the front *b*⁴ of the box or casing to form a deep space *d*, having a supplemental bottom *d*² inclined downwardly from the right to the 70 left as clearly shown in Fig. 3, said bottom being provided with a felt or similar covering *d*³.

The supplemental bottom *c* extends from the right wall *b*³ to a supplemental side wall *b*⁶ within the left wall *b*³, said wall *b*⁶ and the left wall *b*³ forming a deep space *e* having a supplemental bottom *e*² provided with a felt covering *e*³ as clearly shown in Fig. 3. The bottom *e*² is inclined upwardly and 75 backwardly as indicated in dotted lines in Fig. 2, and the rear end thereof is in the same transverse plane as the rear end of the supplemental bottom *c*.

Pivoted to the top rear end portion of the 80 side wall *b*³ is a transverse plate *f*, and the supplemental side wall *b*⁶ extends above the supplemental bottom *c* and said extension runs from the front of the supplemental bottom *c* to the front portion of the plate *f*, as clearly shown at *c*⁴ in Fig. 2, and secured to the rear corner portions of the box 85 or casing *b* above the supplemental bottom *c* are triangular-shaped cushion members *g*.

The front wall *b*⁴ is provided adjacent 90 to the top thereof with a transverse aperture or opening *b*⁷ which extends approximately the full width of the supplemental bottom *c*, and is provided with a sheet metal facing *b*⁸, as clearly shown in Figs. 1 and 2.

A push rod *h* is mounted in the front 95 lower left hand corner of the box or casing and centrally of the space *e* therein, and the inner end of said rod is provided with an enlarged head *h*² between which and the front wall *b*⁴ of the box or casing is placed a coil spring *h*³ which serves to force said rod inwardly, and the outer end of said rod 100

105

is provided with a handle member h^4 . The space d at the front of the box or casing is provided at the left hand portion thereof with a beveled runway d^4 which serves to 5 guide a spherical member dropped in said space, as hereinafter described.

I also provide a hand-operated pointer device i which is adapted to be operated through the aperture or opening b^7 in the 10 front wall b^4 , and which comprises a handle member i^2 inwardly of which is a transverse and depending member i^3 which serves to limit the inward movement thereof, and the inner end portion of said device comprises a shank having a head i^4 which is 15 preferably triangular in form and which is provided with a pointer, pin or similar device i^5 , and the shape of the head i^4 and the dimensions thereof is such as to permit said head to be freely passed through and withdrawn from the aperture or opening b^7 in the 20 operation of playing the game as hereinafter described.

In practice, I employ one or more spherical members j having three series of beveled apertures therein, two of said series consisting of apertures j^2 , j^3 , j^4 , j^5 and j^6 , and the other of said series consisting of a plurality of apertures j^7 arranged in a common plane around the periphery of said spherical member j . The apertures j^7 are 25 alternately numbered 5, 10, 5, 10, etc., while the other series of apertures designated by the reference characters j^2 to j^6 inclusive, 30 are successively numbered 25, 50, 75, 100 and 200.

The game may be played a number of ways, and will doubtless be modified by 35 those playing the same, and any number of 40 players, within certain limits, may play in a single game, and for explanation the following description of one game in which two players A and B are playing is submitted.

As in other games of a similar class, the 45 game may consist of any predetermined number of plays by each player and for illustration we will presume that each player will have ten plays.

Presuming A is playing, one of the 50 spherical members is dropped into the space e and the push rod h drawn out by the left hand against the tension of the spring h^3 and quickly released, which operation moves the spherical member up the supplemental 55 inclined bottom e^2 of said space till it strikes the cushion members g at the left, and said members direct the said spherical member inwardly onto the supplemental bottom e , or the table of the game device, and by reason 60 of the fact that said table is inclined downwardly and forwardly, said spherical member moves forwardly and the pointer device i is operated by the player, in the aperture or opening b^7 , to catch the said 65 spherical member on the point of said

pointer device by inserting the point of said device into one of the apertures in said spherical member, a further object of the player being to insert the point of the pointer device into the aperture in said spherical member, which bears the greatest number, or into the aperture designated by the numeral 200.

In order that the play just performed should count said spherical member must be 70 raised from the table by means of the pointer device i , as indicated in Fig. 2, and if this result cannot be performed the play does not count, and if the party playing, or A, should fail to strike one of the apertures in the spherical member, or catch said member on the end of the pointer device, and the said spherical member passes by the pointer device and drops into the space d , A, the player, of course would receive no 80 count.

After A has finished his ten plays, it is B's turn to play and he proceeds in the same manner as A and the total of all the counts made during the ten plays of each player 90 determines as to who wins the game.

It will also be understood that, if desired, a game may consist of a series of parts, each consisting of a predetermined number of plays, and any predetermined number of 95 points may be played and, if desired, a number of points say 5000 may be named and the player first reaching this number wins the game.

It would involve a game consisting of ten 100 parts having ten plays each for any player to average the above amount, and as the time required for playing each part is short the game will be kept lively and of great interest to the players.

It will also be understood that the arrangement of the apertures in the spherical member and the values thereof may be modified to any desired extent, and a number of spherical members having different 110 arrangements of apertures and designating numerals may be used in connection with the game, and in this way games of different character and involving different methods of playing and counting may be played. 115

While I have shown and described the preferred form of my improved game device, my invention is not limited to the details herein shown and described, and changes therein and modifications thereof 120 may be made, within the scope of the appended claims, without departing from the spirit of my invention or sacrificing its advantages.

Having fully described my invention, what 125 I claim as new and desire to secure by Letters Patent, is:—

1. A game device comprising a suitable table and a perforated spherical member, means for manipulating said member to 130

- move it over said table, and means movable over said table and adapted to engage the perforations in said spherical member.
2. A game device comprising an inclined table, a perforated member movable there-over, means for manipulating said member to bring it onto said table, and means adapted to engage the perforations in said member in its movement over said table.
- 10 3. A game device, comprising an inclined table, a perforated member movable there-over, means for manipulating said member to bring it onto said table, and a pointed member movable over said table and adapted to engage the perforations in said perforated member.
4. In a game device, an oblong box or casing comprising an inclined table, the front of which communicates with a deep trans-
20 verse space having an inclined bottom, and a supplemental side wall between which and the adjacent wall is a deep longitudinal space having an inclined bottom, the bottoms of each of said spaces inclining from a common corner of the box or casing, a spring-operated device mounted in said corner, a perforated member adapted to be operated by said spring-operated device to move it onto said inclined table, and means
25 movable over said table and adapted to enter the perforations in said member.
5. In a game device, an oblong box or casing comprising an inclined table, the front of which communicates with a deep trans-
30 verse space having an inclined bottom, and a supplemental side wall between which and the adjacent wall is a deep longitudinal space having an inclined bottom, the bottoms of each of said spaces inclining from a common corner of the box or casing, a spring-operated device mounted in said corner, a perforated member adapted to be operated by said spring-operated device to move it onto said inclined table, and a hand-
35 operated member movable through a trans-
40 verse slot in said box or casing and one end of which is pointed to enter the perforations in said perforated member.
6. A game device of the class described, comprising a box or casing having an inclined bottom or table portion, and a spherical member having radial apertures, mechanical means for depositing said member on the higher end portion of said table, and a device movable over the lower end portion of said table to engage the apertures in said spherical member.
- 50 7. A game device of the class described, comprising a box or casing having a table inclined from one end portion thereof to the other, and a spherical member having transverse or radial apertures, mechanical means for placing the spherical member on the higher end portion of said table and a hand-operated device movable transversely of the lower end of said table and adapted to engage the apertures in said spherical member.
- 55 8. A game device of the class described, comprising a box or casing having a table portion inclined from one end of the box or casing to the other, the end wall of the box or casing at the lower end of said table portion being provided with a transverse aperture, a spherical member movable over said table portion and provided with transverse apertures, mechanical means for placing the spherical member on the higher end portion of said table, and a hand-operated device movable through an aperture in the end wall of the box or casing and adapted to engage the apertures in the spherical member.
- 60 In testimony that I claim the foregoing as my invention I have signed my name, in presence of the subscribing witnesses, this 26th day of March, 1917.

SAMPSON SCHUYLER.
